UNITED STATES PATENT OFFICE.

GUSTAVE YSEBOODT, OF BRUSSELS, AND ROBERT HENRI MAUTSCH, OF CORTENBERG,
BELGIUM.

BLOCK-SIGNALING ARRANGEMENT AND THE LIKE.

Application filed March 18, 1914. Serial No. 825,633.

To all whom it may concern:

Be it known that we, GUSTAVE YSEBOODT and ROBERT HENRI MAUTSCH, subjects of the King of the Belgians, residing at Brussels, and Cortenberg, Province of Brabant, respectively, both in the Kingdom of Belgium, have invented certain new and useful Improvements in and Relating to Block-Signaling Arrangements and the like, of which the following is a specification.

The present invention relates to improvements in and relating to apparatus and installations for regulating trains known as the "block system". Such systems previously employed continuous currents, single phase alternating currents or the like and have always been open to the objection that it is possible to obtain a false signal by these means. For instance contacts between the wires themselves, contacts of these wires with the earth, variations in the resistance of the earthing connections and atmospheric discharges or contact with other wires through which current passes which are capable of operating the instruments would each cause a false signal to be performed. This is particularly the case in which the lines are in the open and on which telegraphic, telephonic and other controlling and communicating wires are all carried upon the same posts. These defects also take place with cables as well as with overhead wires and the object of the present invention is to entirely eliminate this objection.

One object of the invention is to provide apparatus responsive to a selection of simultaneously operating currents in order to avoid the possibility of accidental operation of the signal.

Another object of the invention is to provide a means to ensure regular operation of the apparatus by the operators at each station.

According to the present invention a number of currents are supplied simultaneously so as to operate members which will release for manual or other operation the signals of whatever type these may be, semaphore or otherwise. These currents for instance may be polyphase and in a preferred form three phase. This is particularly advantageous as three phase current is very seldom if ever employed on the same poles as are used for carrying the wires for the block apparatus and further even if so used the

danger of two or three wires being simultaneously in connection is such as to be practically negligible. By using three phase current or the like it is possible to ensure that the transmitting member must be operated between the successive acceptance of two trains running in the same direction, for instance when the receiving member is a motor it may be arranged so that when rotated in one direction it will release the signal while a second release of the signal cannot take place until its direction of rotation has been reversed, that is to say until two of the phases of the currents sent out have been reversed.

The various apparatus for performing the necessary operation for a blocking system will be described with reference to the accompanying drawings, in which the apparatus are shown diagrammatically. This invention is capable of numerous applications as will be readily understood but is described with reference to a three phase current system.

Fig. 1 shows the arrangement of the transmitting and receiving stations with the receiver rotating in either direction.

Fig. 2 shows the receiving apparatus after the rotation of the motor and before the lowering of the signal.

Fig. 3 shows the receiving apparatus after the first raising of the signal.

Fig. 4 shows the apparatus at both stations when a unidirectional rotation of the receiver is desired.

Fig. 5 shows the receiver apparatus after the first transmission of three phase currents.

In general the invention relates to a plurality of stations each having a transmitting and receiving apparatus, the transmitter at one station being connected to the receiver at the next and so on. The receiving apparatus is such that when three phase current generated at the transmitting station is received, an asynchronous three phase motor rotates to free the signal lever which can then be operated. The movement of the lever controlling the signal arm causes the characteristics of the receiving apparatus to be altered in that either two phases of the receiving motor are reversed or the shaft of the receiving motor is mechanically prevented from rotating a second time in the same direction. Both cases necessitate the

reversal of two phases of the current generated at the transmitter which is automatically effected on the restoration of the transmitting device to its normal position 5 between the acceptance of two successive trains.

In the first method of operation of this system to which Figs. 1, 2 and 3 refer, the direction of rotation of the asynchronous 10 motor of the receiver at the up station changes at each acceptance in consequence of the disposition of the mechanism of this receiver and thus requires a reversal of two phases of the three phase current at the 15 transmitting station. This is effected by the replacement of the transmitter in its normal position between two successive acceptances.

Fig. 1 shows a block system comprising two stations A and B connected by the 20 ducting wires 1 and 2 and also by the earth return shown connected to earth at 3 and 4. The station A includes a signal 5 belonging to the section of the line between the two stations in the direction of travel from 25 A to B, and a three phase asynchronous motor comprising a stator 6 and a rotor 60 operating the mechanism of the receiver which unlocks the signal. The station B comprises a generator of three phase current 8, the transmitter 9 actuating the line switches 10 and 11 as well as the phase changer 12.

Fig. 1 shows the apparatus in a normal position that is to say the position that they 35 occupy when no train is passing through this section of the line. In this position it will be seen that the operating lever 7 of the signal is held fast by the elements 13, 14 and 15. The lever 7 turns freely 40 round the spindle 16 which it rotates only in one direction by means of the ratchet 17 during the operation of lowering the signal. The cam 18 mounted on the shaft 16 operates a change at each operation of 45 the signal the position of the levers 19 and 20 turning freely about the axis 21.

It will be seen that in the position shown in Fig. 1 of the drawing the levers 19 and 20 allow the axis 22 to turn only in the direction of the arrow 23. After the lowering 50 of the signal the levers 19 and 20 will change their position and the spindle 22 will be able to turn only in the opposite direction to that shown by the arrow 23.

55 The three phase motor rotates the spindle 22 through the intermediary of a train of gears 24 and a friction device 25 in one or other direction according to the inversion of the three phase currents transmitted by the 60 station B. The friction device 25 serves to damp the movement of the motor when the cam 15 meets one or the other of the stopping abutments 26 and 27.

In operation, in order to instruct the station A to lower the signal 5, the station B

pushes down his transmitting apparatus 9 and rotates the generator 8 and sends in this way three phase current to the station A.

Fig. 1 shows clearly the path taken by the three phase current through the intermediary of the two conductors 1 and 2 and the earth return. If the currents in the phases are suitably cummuted to effect this first acceptance the axis 22 turns in the direction of the arrow 23 and the mechanism of the receiver at the station A takes up at the end of the operation the position shown in Fig. 2. This figure shows that the element 13 connected to the lever 7 is freed and that the signal 5 can be lowered.

When the lever 7 is pulled back a projection 28 of the rod 29 which is connected to the lever 7 and which slides on the fixed rod 30 takes up its position in front of one end of the cog 31 fixed on the spindle 22. On the other hand during its pulling back movement the lever 7 draws the spindle 16 by means of the ratchet 17 and thus changes the positions of the levers 19 and 20 by means of the cog 18. During the operation of raising the signal the projection 28 meets the cog 31 which results in the turning of the spindle 22 in the opposite direction in such a way as to cause it to take up the position which it occupied previously. At the end of 95 this operation when the lever 7 is completely returned to its normal position the mechanism of the receiver also takes up its normal position that is to say that in which the lever 7 is stationary.

It will be seen in Fig. 3 that the cog 15 should now turn in the direction of the arrow 32 for the following acceptance owing to the new position occupied by the levers 19 and 20. It will be seen indeed that the cog 50 105 will butt against the lever 19 if the three phase motor again turns in the same direction for the following acceptance.

It is therefore absolutely necessary in order to clear the station A a second time for the station B to send him the reversed three phase currents. This changing over is automatically effected when the operator at station B allows the transmitter 9 again to take up its normal position after the sending of 115 an acceptance. It will be seen indeed that the transmitter 9 rotates on the return movement by the combined operation of the ratchet 33 and of the catch 34 the phase changer 12 which changes in a suitable manner after each regular operation of the transmitter 9 two of the phases of the three phase current.

For the following acceptance the cog 15 will turn in the direction of the arrow 32 125 and will meet, at the end of this path, the abutment 27. In this position the cog 15 brings the notch 52 opposite the member 14 which will thus be displaced and free the element 13. During the lowering of the sig- 130

nal the lever 7 rotates, as in the preceding operation, the cog 18 by means of the ratchet 17 and will change in this way the position of the levers 19 and 20 which will thus take up the positions they occupied before the first acceptance. During the operation of closing the signal it will be seen that the projection 35 of the member 36 which is connected to the lever 7 and which slides on the fixed member 37 will this time meet the lower extremity of the cog 31 which results in causing the spindle 22 to turn and in this way cause the cog 15 to take up its normal position.

15. The figures clearly show the function of the various return springs. What has already been said shows that it is possible by the use of three phase currents suitably changed for each operation at the transmitting station to enforce the signallers to operate regularly the apparatus, that is to say, to force them to replace the transmitting device in its normal position between two successive acceptances. In consequence if the transmitter 9 is locked by an arrangement on the track either mechanical or electrical operated by the train itself, safety will be completely ensured.

20. In the second method of carrying out this invention to which Figs. 4 and 5 refer the asynchronous motor of the receiving station always turns in the same direction in order to free the bolt which locks the signal lever of the same section of the line, the phases of this motor being changed at the receiving station between two successive acceptances thus enforcing a second changing of phases at the transmitting station which is effected by putting back in the normal position the 25 transmitter of this station between two successive acceptances.

25. Fig. 4 shows a block system comprising two stations A and B adapted to serve the section of the line between the two stations in the direction A towards B. The two stations are connected by two wires 1 and 2 and by an earth wire at 3 and 4. The station A comprises a signal 5 protecting the section of the line above mentioned, a three phase asynchronous motor comprising a stator 6 and a rotor 60 actuating the mechanism of the receiver which locks the signal 5. The station B comprises a three phase current generator 8, a transmitting device 9 operating line switches 10 and 11 and also the phase rectifier 12 by means of the ratchet 33 and the holding device 34.

30. In operation it will be seen that in the position shown the operating lever 7 of the signal 5 is rendered stationary by the elements 13, 14 and 15, the lever 7 turns freely round its axis 16 which it turns always in the same direction during the lowering of the signal by means of a ratchet 17 and of the holding device 40. The phase

rectifier 41 fixed on the spindle 16 reverses at each operation of lowering the signal two of the phases of the motor.

35. Fig. 4 shows that the spindle 22 on which is fixed the cog 15 ought to turn always in the direction of the arrow 23 in order to free the lever 7. In order to instruct the station A to lower the signal 5 the operator at the station B moves his transmitting device 9 downwards and sends in this way three phase currents to the station A. Fig. 4 shows clearly the path taken by the three phase currents along the two conductors and earth. If the three phase currents are suitably changed in order to effect this first acceptance, the spindle 22 rotated by means of the train of gears 24 and the friction device 25 turns in the direction of the arrow 23. At the end of the operation the mechanism of the receiver takes up the position shown by Fig. 5. The lever 7 can thus be drawn back to lower the signal 5. During the withdrawal of the lever 7 the phase rectifier 41 changes as has been explained above two of the phases of the motor.

40. During the closing operation the projection 28 of the member 29 which is fixed to the lever 7 and which slides along the fixed member 30 comes in contact with the cog 31 fixed on the spindle 22 which results in the rotation of this spindle in the opposite direction to that shown by the arrow 23 and in the replacement of the cog 15 in its normal position that is to say that which it occupies in Fig. 4. The lever 7 is again rendered immovable and it is necessary in order to free it a second time that the spindle 22 again turns in the direction of the arrow 23, that is to say the motor turns again in the same direction. But as two phases of the motor have been reversed by the phase rectifier 41 during the previous lowering movement of the signal it is necessary that the station B should send to the station A, for this new acceptance, currents which are suitably reversed and this cannot take place unless the operator at station B has replaced the transmitter 9 in its normal position after the dispatch of the first acceptance. It is only indeed in these conditions that the ratchet 33 and the holding device 34 ensure regular operation of the phase rectifier 12.

45. Figs. 4 and 5 show clearly the function of the various return springs. The preceding description shows that it is possible by the use of three phase currents suitably commutated at each operation at the transmitting station and at the receiving station to enforce on the signallers the obligation of replacing the transmitting device in its normal position between two successive acceptances. From this it results that if the transmitter 9 is locked by an arrangement on the track either mechanical or electrical actuated

ed by the train itself, safety will be insured in a complete manner.

We declare that what we claim is:

1. In a block signaling system the combination of a plurality of stations, connecting means between said stations, transmitting apparatus at the up-line station, receiving apparatus at the down-line station, means to generate three phase current at the transmitter, an asynchronous motor at the receiver adapted to be rotated by the said three phase current, a signaling device adapted to be actuated only after the rotation of said motor, means controlling the operation of said signaling device, and means to alter the characteristics of said controlling means on the actuation of said signaling device.

2. In a block signaling system the combination of a plurality of stations, connecting means between said stations, transmitting apparatus at the up-line station, receiving apparatus at the down-line station, means to generate three phase current at the transmitter, an asynchronous motor at the receiver adapted to be rotated by the said three phase current, a signaling device adapted to be actuated only after the rotation of said motor, means controlling the operation of said signaling device, means to alter the characteristics of said controlling means on the actuation of said signaling device, and means at the transmitter to reverse two phases of the three phase current after transmission.

3. In a block signaling system the combination of a plurality of stations, connecting means between said stations, transmitting apparatus at the up-line station, receiving apparatus at the down-line station, means to generate three phase current at the transmitter, an asynchronous motor at the receiver adapted to be rotated by the said three phase current, a signaling device adapted to be actuated only after the rotation of said motor, means controlling the operation of said signaling device, means to alter the characteristics of said controlling means on the actuation of said signaling device, and automatic means at the transmitter to reverse two phases of the three phase current after transmission.

4. In a block signaling system the combination of a plurality of stations, connecting means between said stations, transmitting apparatus at the up-line station, receiving apparatus at the down-line station, a manually operated rotating generator at the transmitting station generating three phase current, an asynchronous motor at the receiver adapted to be rotated by the said three phase current, a signaling device adapted to be actuated only after the rotation of said motor, means controlling the operation of said signaling device,

and means to alter the characteristics of said controlling means on the actuation of said signaling device.

5. In a block signaling system the combination of a plurality of stations, connecting means between said stations, transmitting apparatus at the up-line station, receiving apparatus at the down-line station, means to generate three phase current at the transmitter, an asynchronous motor at the receiver adapted to be rotated by the said three phase current, a signaling device adapted to be actuated only after the rotation of said motor, means controlling the operation of said signaling device, means to alter the characteristics of said controlling means on the actuation of said signaling device, and means at the transmitter to reverse two phases of the three phase current only on replacement of the transmitting apparatus in its normal position.

6. In a block signaling system the combination of a plurality of stations, connecting means between said stations, transmitting apparatus at the up-line station, receiving apparatus at the down-line station, a manually operated generator at the transmitter generating three phase current, an asynchronous motor at the receiver having its rotor mounted on a spindle and adapted to be rotated by the said current, a signaling device, means for controlling said signaling device adapted to be put in operative position by the rotation of said motor, automatic means at the transmitter to reverse two phases of the generator current, and means at the receiver to alter the characteristics of said receiver during each operation of said signaling device.

7. In a block signaling system the combination of a plurality of stations, connecting means between said stations, transmitting apparatus at the up-line station, receiving apparatus at the down-line station, a manually operated generator at the transmitter generating three phase current, an asynchronous motor at the receiver having its rotor mounted on a spindle and adapted to be rotated by said current, a signaling device, an operating lever for said signaling device adapted to be normally locked in position, means mounted on said rotor spindle to release said locking means, automatic means at the transmitter to reverse two phases of the generator current, and means at the receiver to alter the characteristics of said receiver during each operation of said signaling device.

8. In a block signaling system the combination of a plurality of stations, connecting means between said stations, transmitting apparatus at the up-line station, receiving apparatus at the down-line station, a manually operated generator at the transmitter generating three phase current, an asyn-

chronous motor at the receiver having its rotor mounted on a spindle and adapted to be rotated by said current, a signaling device, an operating lever for said signaling device adapted to be normally locked in position, means mounted on said rotor spindle to release said locking means, a phase rectifier at said transmitter to reverse two phases of said generator current, and means at the receiver to alter the characteristics of said receiver during each operation of said signaling device.

9. In a block signaling system the combination of a plurality of stations, connecting means between said stations, transmitting apparatus at the up-line station, receiving apparatus at the down-line station, a manually operated generator at the transmitter generating three phase current, an asynchronous motor at the receiver having its rotor mounted on a spindle and adapted to be rotated by said current, a signaling device, an operating lever for said signaling device adapted to be normally locked in position, means mounted on said rotor spindle to release said locking means, a phase rectifier at said transmitter to reverse two phases of said generator current, and a phase rectifier at the receiver adapted to reverse the connections of said asynchronous motor.

10. In a block signaling system, the combination of a plurality of stations, connecting means between said stations, transmitting apparatus at the up-line station, receiving apparatus at the down-line station, means to generate three phase current at said transmitter, an asynchronous motor at the receiver having its rotor mounted on a spindle adapted to be actuated by said current, a signaling device controlling the line between said stations, a lever operating said signaling device and normally locked in position, releasing means on said rotor spindle adapted to release said locking means on the rotation of said motor, a phase rectifier at the receiver to reverse the connections of two phases of said asynchronous motor adapted to be actuated on the operation of said lever, and a phase rectifier at said transmitter to reverse two phases of said three phase current.

11. In a block signaling system the combination of a plurality of stations, connecting means between said stations, transmitting apparatus at the up-line station, receiving apparatus at the down-line station, means to generate three phase current at said transmitter, an asynchronous motor at the receiver having its rotor mounted on a spindle adapted to be actuated by said cur-

rent, a signaling device controlling the line between said stations, a lever operating said signaling device and normally locked in position, releasing means on said rotor spindle adapted to release said locking means on the rotation of said motor, a phase rectifier at the receiver to reverse the connections of two phases of said asynchronous motor adapted to be actuated on the operation of said lever, and a phase rectifier at said transmitter to reverse two phases of said three phase current only when the transmitting apparatus is restored to its normal position.

12. In a block signaling system the combination of a pair of adjacent inter-connected stations, transmitting apparatus at the up-line station, receiving apparatus at the down-line station, connecting means between said transmitting and receiving apparatus, means to generate three phase current at the transmitter, an asynchronous motor at the receiver adapted to be rotated by said three phase current, a signaling device, means controlling the operation of said device and actuated by said motor, and means to alter the characteristics of said receiving apparatus on the operation of said signaling device.

13. In a block signaling system the combination of a pair of adjacent inter-connected stations, transmitting apparatus at the up-line station, receiving apparatus at the down line station, connecting means between said transmitting and receiving apparatus, means to generate three phase current at the transmitter, an asynchronous motor at the receiver adapted to be rotated by said three phase current, a signaling device, means controlling the operation of said device and actuated by said motor, means to alter the characteristics of said receiving apparatus on the operation of said signalling device, and means at the transmitter to reverse two phases of said current on the replacement of said transmitting apparatus in its normal position.

In witness whereof, we have hereunto signed our names this 7th day of March, 1914, in the presence of two subscribing witnesses.
